(57) **CLAIM**

The ornamental design for an automotive rear diffuser, as shown and described.

DESCRIPTION

FIG. 1 is a left rear perspective view of an automotive rear diffuser shown with environment;

FIG. 2 is a right and rear perspective view thereof;

FIG. 3 is a right, bottom, and rear perspective view thereof;

FIG. 4 is a rear elevation view thereof;

FIG. 5 is a front elevation view thereof;

FIG. 6 is a left side elevation view thereof;

FIG. 7 is a right side elevation view thereof;

FIG. 8 is a top plan view thereof; and,

FIG. 9 is a bottom plan view thereof.

The broken lines in the drawings illustrate portions of the automotive rear diffuser that form no part of the claimed design.

1 Claim, 7 Drawing Sheets
